(57) **CLAIM**

The ornamental design for a machine for sorting or classifying particulate products such as foodstuffs, as shown and described.

DESCRIPTION

FIG. 1 is a front view of a machine for sorting or classifying particulate products such as foodstuffs showing my design.

FIG. 2 is a rear view thereof.

FIG. 3 is a right side view thereof.

FIG. 4 is a left side view thereof.

FIG. 5 is a top view thereof.

FIG. 6 is a bottom view thereof; and,

FIG. 7 is a perspective view thereof.

The broken line showing in FIGS. 1–7 is for the purpose of illustrating portions of the machine for sorting or classifying particulate products such as foodstuffs and forms no part of the claimed design.
